UNITED STATES PATENT OFFICE.

THOMAS SCHOCK, OF EUGENE, OREGON.

STEAM-SHOVEL.

1,074,018.

Specification of Letters Patent.

Patented Sept. 23, 1913.

Application filed September 23, 1912. Serial No. 721,970.

To all whom it may concern:

Be it known that I, THOMAS SCHOCK, a citizen of the United States, and resident of Eugene, in the county of Lane and State 5 of Oregon, have invented new and useful Improvements in Steam-Shovels, of which the following is a specification.

My invention relates to a portable digging apparatus of the type usually known as a 10 steam shovel and has for its object, in a general sense, to provide such a machine of simple and inexpensive construction.

One of the more specific objects of my invention is to introduce a novel means of 15 supporting the boom of the machine, in order to readily adapt the machine for various purposes, such as side cutting, thorough cutting or trench cutting.

A further object is to embody a bucket 20 shaped dipper and to hang said dipper on a carriage, which in turn is mounted to travel on said boom, all for the purpose to be hereinafter more fully explained.

In order to facilitate the reading of the 25 following description, a drawing is hereto annexed, in which is illustrated the principle and operation of my device.

In the drawing: Figure 1 is a side elevation of my machine, showing different positions of the machine during its operation, and Fig. 2 shows, in front elevation, some of the parts of the machine.

The machine is mounted to rotate on a wheel truck 1 in any suitable manner, as by 35 a power driven pinion 2 of the machine engaging a gear 3 of the truck. On machine platform 4 is mounted a power unit comprising a boiler 5 and a steam engine 6, the latter operatively connected to rotate a series of drums 7, 8 and 27. On the platform 4, in front of the said drums, is pivotally 40 hung a boom 9, from the outer end of which extends a cable 10, said cable having its inner end secured on the first named drum 7. On the pivot 11, by means of which the boom is supported, is journaled an arm 12, the upper end of which is perforated to 45 rotatably support a sheave 13. The said arm is held in position by means of a link 14, said link connecting the upper end of the arm with a portion of the machine frame. By referring to the drawing it is readily seen how the drum 7, in rotating, raises and 50 lowers the boom as conditions require. The boom is made from a steel bar, presenting in cross section the shape of an I-

beam, or it may be composed of two channel irons, riveted back to back, as shown in Fig. 2. A dipper carriage, comprising a frame 15 provided with a series of rollers 60 16, is mounted to travel in the side channels of the boom, and on the lower end of said frame is pivotally supported a dipper 17. Said carriage is operatively connected with the drum 8 of the engine by means of an 65 endless cable 18, which unwinds from the drum, passes over an idler 19 at the end of the boom, from which it extends underneath the boom and over a second idler 20, thence returning to the drum. The dipper 70 frame is rigidly secured to the lower strand of the cable 18. By rotating the drum 8, the said frame, carrying the dipper, is caused to travel back and forth on the boom. It is noticed that the idler 20 is mounted to 75 rotate on the boom pivot 11, the boom may therefore be adjusted to any required position without interfering with the working of the dipper mechanism.

The front portion of the boom is curved 80 so as to give the bucket a circular sweep during the digging operation. A series of idlers 21 are rotatably mounted on the curved portion of the boom for the purpose of guiding the lower strand of the dipper 85 cable 18. As already stated, the dipper is made in the form of a bucket, said bucket comprising two halves 17^a and 17^b. The said halves are held locked together by a suitable latch mechanism 22. From the releasing bolt 23 of said latch mechanism extends a cable 24 to an endless cable 25, and the latter is hung on idlers positioned adjacent to and on the pivots of the idlers 19, 20 and 21. During the travel of the dipper 90 on the boom it is necessary that the cable 25, termed the trip cable, follow the movement of the bucket. This may be accomplished by extending said cable over the drum 27, which is mounted on the shaft of 95 the drum 8 and connected for rotation by the engine. The drums 8 and 27 in that case should be of the same diameter.

Referring now to Fig. 1, the boom 9, as indicated in full outline, is positioned correctly for grading or for making a thorough-cut. The dipper is caused to move to take in dirt, and when completely filled, the boom is elevated to the position shown in dotted outline, as indicated by 9^a. The 105 whole machine is then caused to turn on the truck until the bucket reaches a point di-

rectly above the unloading place. The dirt drops by gravity into the desired receptacle or to the ground. The machine is then returned to its initial position, and the bucket 5 on reaching the ground snaps closed.

By lowering the boom to the position indicated at 9^b it is possible to dig a trench, excavate for a foundation or perform any other digging operation below the surface 10 level of the truck.

As the construction of the component parts of the machine is well known to those versed in the art, no stress has been laid on illustrating or explaining its mechanical 15 details, it being thought sufficient to take care that the principle and operation of my device is clearly shown and described. It is therefore understood that minor improvements and changes may be made in order 20 to produce a perfect working machine, and so as to simplify its construction, without thereby departing from the principle of my invention. It is also understood that the engine is provided with the usual brake 25 mechanisms, and that the drums are mounted for independent operation by hand lever control or its equivalent.

I claim:

1. In a device of the character described, 30 the combination with a prime mover; of a pivoted boom connected for operation with said prime mover; a dipper frame mounted to travel on said boom; means for operatively connecting said frame with said 35 prime mover for movement in both directions; a bucket pivotally hung on said frame, said bucket comprising two halves each of which has an independent cutting edge whereby said bucket is capable of performing its function in both directions; a 40 latch-mechanism for inter-locking said halves; and means operated by said prime mover for disconnecting said bucket halves.

2. In a device of the character described, 45 the combination with a prime mover and a series of cable drums operable by said prime mover; of a pivoted boom connected for independent operation with one of said drums, the outer portion of said boom 50 curved upwardly; a dipper frame mounted to travel on said boom; an endless cable hung on a second drum of the series and fixed on said dipper frame; means for guiding said cable over the curved portion 55 of the boom; and a bucket pivotally hung in said dipper frame, said bucket made in two portions, each portion having an independent cutting edge, one of which performs its function in one direction while the 60 other operates in the opposite direction.

3. In a device of the character described, the combination with a series of cable drums mounted for independent operation; of a pivoted boom connected for operation with one of said drums, the outer portion of said boom 65 curved upwardly; a dipper frame mounted to travel on said boom through the medium of a second drum of the series; a bucket pivotally hung in said dipper frame, said bucket made in two halves having each 70 a cutting edge so as to permit the bucket to operate in either direction; means for inter-locking the bucket portions; an endless trip-cable hung on a third drum of the series and looped around the boom; means 75 for guiding said trip-cable over the curved portion of the boom; and a short cable inter-connecting said inter-locking means with said trip-cable for the purpose of disconnecting the bucket portions. 80

4. In a device of the character described, the combination with a series of cable drums mounted for independent operation; of a pivoted boom connected for operation with the first drum, the outer portion of said 85 boom curved upwardly; a dipper frame mounted to travel on said boom and moved by the second drum; a bucket pivotally hung in said dipper frame, said bucket comprising two halves having each a cutting edge so as to permit the bucket to 90 operate in either direction; a latch for inter-locking said halves; a bolt for releasing said latch; an endless trip-cable wound on the third drum of the series and looped 95 around the boom; means for guiding said trip-cable over the curved portion of the boom; and a short cable inter-connecting said trip-cable and said bolt; the devices so arranged that the trip-cable normally follows the travel of the dipper frame, and so 100 that the changing of the movement of the trip-cable relative to the said frame causes the said bolt to disconnect the bucket halves.

5. In a device of the character described, 105 a traveling bucket made in two portions, each portion having an independent cutting edge whereby the bucket is enabled to perform its function in either direction, means for interlocking the two portions and means 110 for releasing said inter-locking means, said means including an endless trip-cable normally following the travel of the bucket and independently movable relative to said bucket for the purpose of effecting said release. 115
